LIFT PLUG VALVE

Ferdinand Hinrichs, Kenosha, Wis., assignor to
 Tri-Clover Machine Co., Kenosha, Wis., a corporation of Wisconsin

Application March 6, 1947, Serial No. 732,809

2 Claims. (Cl. 251—97)

1

This invention relates to improvements in lift plug valves.

Plug valves, employing a tapered valve member rotatable in a tapered bore, are commonly employed to control the flow of liquid through a conduit. This type of valve has many desirable features, but is nevertheless objectionable in that the valve member frequently becomes stuck in the tapered bore, and the use of a hammer or other pounding tool is often required to loosen the plug and lift it from its seat, and such pounding is sometimes done so carelessly that parts are broken. Heretofore, various devices have been proposed for dislodging the plug to permit rotation thereof, but these devices have either embodied too many parts to be practical or have embodied interior threading, shoulders or recesses located in objectionable places whereby cleaning of the parts is rendered difficult or impossible. When plug valves are employed in pasteurizing equipment or in other apparatus where a high degree of sanitation is required and where the valves must be taken apart daily for cleaning, quick assembly and disassembly is essential and it is also essential that all of the valve parts be so constructed that every portion thereof is easily accessible for scrubbing. Furthermore, the fewer the number of parts the less the time that is required for taking down, cleaning, and reassembling.

It is therefore an object of the present invention to provide a lift plug valve having a minimum number of parts which are so arranged and constructed that the valve may be quickly assembled and disassembled, each part being so formed that thorough cleaning is a simple matter.

A further object of the invention is to provide a valve as above described including novel means for forcibly moving the plug a short distance in an axial direction so as to force it out of seated condition when it becomes stuck.

A further object of the invention is to provide a lift plug valve as above described wherein the valve operating handle may be rotated without causing a corresponding rotating movement of the cover plate for the valve body, as distinguished from the constructions illustrated in copending applications of Thomas Geary, Serial No. 732,708, filed March 6, 1947, and now abandoned, and Walter Ebert, Serial No. 732,706, filed March 6, 1947, and which matured to Patent No. 2,529,544 on November 14, 1950, wherein the cover plate rotates whenever the operating handle is turned.

A still further object of the invention is to provide a lift plug valve as above described

2

wherein rocking movement of a single operating handle in one direction or another prior to rotating movement thereof serves to loosen the valve in its seat.

5 A still further object of the invention is to provide a lift plug valve wherein the operating handle is removably connected to the projecting stem portion of the valve member by a spring clip, the parts being so constructed that a simple manipulation of the clip serves to releasably lock the handle in assembled position.

A more specific object of the invention is to provide a lift plug valve as above described wherein the lower end of the plug has a depending stem with a threaded outer end portion for receiving a nut, there being yielding means inwardly of the nut and surrounding said stem for normally urging the plug into seated condition.

With the above and other objects in view, the 20 invention consists of the improved lift plug valve, and all its parts and combinations, as set forth in the claims, and all equivalents thereof.

In the accompanying drawing, illustrating one 25 complete embodiment of the preferred form of the invention, in which the same reference numerals designate the same parts in all of the views:

Fig. 1 is a longitudinal sectional view through the valve, with most of the plug member and 30 part of the handle shown in full, the dot and dash lines indicating rocked positions of the handle;

Fig. 2 is a sectional view taken on the line 2—2 of Fig. 1;

35 Fig. 3 is a fragmentary sectional view taken on the line 3—3 of Fig. 1; and

Fig. 4 is a sectional view taken on the line 4—4 of Fig. 1.

Referring more particularly to the drawing, 40 the numeral 6 designates a valve body having a longitudinal bore 7 and having a transverse tapered bore 8 intersecting the longitudinal bore 7. A valve member or plug 9 is seated in the tapered bore 8 and provided with the usual bore 45 10 which is adapted to be brought into or out of alignment of the bore 7 of the body when the plug is rotated.

The upper end of the plug has a stem 11 projecting upwardly from the center thereof. The 50 stem is adapted to extend rotatably through a circular opening 12 in a cover plate 13. The portion of the stem which projects above the cover plate has a transverse bore 14.

A handle member 15 has its inner end of inverted cup-shape as at 16, said cup-shaped por-

tion having a cavity 17 therein which loosely receives the projecting end of the stem 11. The rim 18 of the cup-shaped portion is preferably rounded as illustrated. When this rim rests on the top surface of the cover plate 13, as in the full line position of Fig. 1, and when the parts are assembled, the cavity 17 provides substantial clearance above the upper end of the stem 11 as at 19 and provides annular clearance around the stem as at 20. This clearance allows for the rocking movement shown by the dot and dash lines.

The side walls of the cup-shaped portion 16 are oppositely apertured as at 21, the latter apertures being adapted to align with the bore 14 of the stem 11 when the parts are in the assembled position.

A clip 22, formed of sturdy wire, has a pintle portion 23 which is readily insertible through the aligned openings 21 and 14 when the clip is in the dot and dash line position A of Fig. 1. The clip includes a side portion 24 bent at right angles to the pintle portion 23, a top portion 25 bent at right angles to the portion 24 and parallel to the pintle portion 23, and an angularly bent retaining end 26. The distance between the pintle portion 23 and the top portion 25 of the clip is such that when the clip is pivoted from the position A to the position B, it has to be forced to snap over the rounded corner 27 of the handle. There is just enough give in the clip to permit this to take place with a minimum of effort. On the other hand, the clip is sufficiently rigid that it will not be accidentally displaced from the position B back to the position A during use. After the clip is in the position B it is normally swung up to the full line position during use. The downwardly bent terminal end 26 is sufficiently long to slightly overhang a side of the cup-shaped portion 16 and prevent lateral displacement of the clip.

Projecting concentrically from the lower end of the plug is a bottom stem portion 28 which is preferably formed with a flat side 29. Below the stem portion 28 is an externally threaded portion 30 of reduced diameter for receiving an adjustment nut 31. In the preferred embodiment of the invention the adjustment nut acts against the lower face of a washer 32, and the latter has an opening 33 which is shaped to fit the flattened cross-section of the stem 28. Thus, the washer will rotate with the stem.

In order to constantly urge the plug into seated position, yielding means is employed around the stem portion 28. This yielding means is so arranged as to constantly urge the plug into seated condition. In the preferred form of the invention this yielding means takes the form of a yielding concavo-convex disc 34 having a central opening 35 through which the stem portion 28 rotatably extends. The periphery of the disc 34 seats against the annular end 36 at the bottom of the valve body. When the nut 31 is suitably adjusted to compress the disc 34 somewhat, the disc will tend to return to its normal concavo-convex form and will thus act against the inner face of the washer 32 to constantly urge the plug 9 into seated condition. The disc also provides a bottom closure for the valve body. Other equivalent arrangements may be employed at the lower end of the valve plug, such as those illustrated in copending application of Thomas Geary, Serial No. 732,708, filed March 6, 1947, and now abandoned, and copending application of Walter Ebert, Serial No. 732,706, filed March

6, 1947, and which matured to Patent No. 2,529,544 on November 14, 1950.

In use of the improved valve, assuming that the valve is in the open position of Fig. 1 and that it is desired to close it, it is merely necessary to manipulate the single handle 15. Depending upon which movement is more convenient for the operator, the handle is rocked either downwardly to the dot and dash line position 10 C, or upwardly to the dot and dash line position D to cause a forcible movement of the plug a short distance in an axial direction to lift it out of seated condition if it has become stuck. During such rocking movement one side or the other of the rim 18 of the cup-shaped handle portion 16 bears against the upper surface of the cover plate 13 so that a lifting movement is imparted to the stem 11 through the medium of the pintle portion 23 of the clip 22. The amount of lift which is possible may be controlled by the amount of clearance between the top of the plug 9 and bottom of the cover plate 13. Where leakage when the valve is unseated is a problem, such leakage can be held down to a minimum by limiting the clearance above the plug 9 to an amount just sufficient for seal-breaking purposes. After the seal has been broken, the handle is rotated to bring the plug to a clasing position. During such rotation of the valve member the washer 32 and nut 31 will rotate with the plug 9, the washer having a sliding engagement with the lower face of the disc 34. Due to the squared fit of the washer on the stem 28 there will be no tendency to loosen the nut 31 during such rotation. During such rotation the handle 15 will rotate with the plug 9, and the plate 13 will remain stationary because the coefficient of friction between the plate 13 and the body 6 is greater than the coefficient of friction between the rim 18 of the handle and the top of the plate 13.

As soon as the handle 15 is released, the yielding disc 34 will pull the plug back to seated condition and the handle will automatically rock to the intermediate full line position.

With the above construction, the same handle which is used for valve rotation is employed for breaking the seal. The construction has been so worked out that there is a minimum number of parts. Furthermore, each part is so constructed that it can be thoroughly cleaned without difficulty. Complete disassembly of the valve can be quickly accomplished by snapping the clip 22 downwardly from the full line position of Fig. 1 past the rounded corner 27 to the dot and dash line position A, by then withdrawing the pintle in a lateral direction, and by removing the nut 31.

Although only one form of the invention has been illustrated, it is obvious that various changes and modifications may be made without departing from the spirit of the invention, and all of such changes are contemplated as may come within the scope of the claims.

What I claim is:

1. In a valve having a valve body provided with a tapered bore and having a ported tapered plug, an actuating mechanism comprising: a cover having an opening, a stem slidable in said opening, said cover having an annular upper surface portion around said opening; a handle normally disposed at a right angle with respect to said stem and having a depending rim portion at its inner end adjacent the projecting end of the stem and rotatable over said annular surface portion of the cover; and a pivot member extending

diametrically through said stem and pivotally connecting the inner end of the handle to the projecting end portion of said stem for rocking movement on the axis of said pivot member, part of said depending rim portion being positioned for fulcruming engagement with a part of the flat annular upper surface portion of the cover on one side of the axis of the stem and part being positioned for fulcruming engagement on the other side of the said axis whereby the handle may be rocked on said pivot member in either of two directions away from a normal position at right angles to the valve stem to impart axial upward movement to the stem.

2. In a valve having a valve body provided with a tapered bore and having a ported tapered plug, an actuating mechanism comprising: a cover having an opening, a stem slideable in said opening, said cover having an annular upper surface portion around said opening; a handle normally disposed at a right angle with respect to said stem and having an inverted cup-shaped portion at its inner end embracing the projecting end of the stem, said cup-shaped portion having an annular lower edge extending in substantially a single plane which is normally at a right angle with respect to said stem, said cup-shaped portion being rotatable over said annular surface portion of the cover as said handle is rotated; and a pivot member extending diametrically through said stem and cup-shaped handle

portion to pivotally connect the inner end of the handle to the projecting end portion of said stem for rocking movement on the axis of said pivot member, whereby the stem is rotated upon rotation of said handle, diametrically opposite parts of said annular lower edge portion being alternatively engageable with parts of the flat annular upper surface portion of the cover on either of two diametrically opposite sides of the stem when the handle is rocked on said pivot member away from its normal position at right angles to the stem to thereby impart axial upward movement to the stem.
